UNITED STATES PATENT OFFICE

98,796

DESIGN FOR A TANK VEHICLE

Robert W. Crossen, Jr., Plainfield, Ill., assignor to Farrell Manufacturing Company, Joliet, Ill., a corporation of Illinois

Application December 6, 1934, Serial No. 54,319

Term of patent 14 years

To all whom it may concern:

Be it known that I, Robert W. Crossen, Jr., a citizen of the United States, residing at Plainfield, in the county of Will and State of Illinois, have invented a new, original, and ornamental Design for a Tank Vehicle, of which the following is a specification, reference being had to the accompanying drawing, forming a part thereof.

Figure 1 is a side elevation of the tank vehicle showing my new design, the tank vehicle appearing substantially the same from the opposite side thereof;

The dominant feature of the design is the unitary appearance presented by the tank and cab portion of the vehicle, substantially as shown, the dotted line disclosure showing the immaterial parts of the design.

I claim:

The ornamental design for a tank vehicle substantially as shown and described.

ROBERT W. CROSSEN, JR.
